BLOOD COLLECTING INSTRUMENT

Errol R. Lawshe, Rutherford, N. J., assignor to
Becton, Dickinson & Co., Rutherford, N. J., a
corporation of New Jersey

Application January 3, 1942, Serial No. 425,492

3 Claims. (Cl. 128—347)

This invention relates to an instrument for use in the withdrawal of blood from a patient, usually from a vein or artery in the patient's arm, and the collection of such blood in a test tube or the like in sufficient amount to be tested. Instruments for this purpose usually comprise a hollow or tubular needle which is sharpened at one end to facilitate its introduction into the vein or artery of the patient and which is provided with some means, such as a clip, to enable the instrument to be clamped on a test tube in such manner that the blunt end of the hollow needle will extend into the tube. Probably the most satisfactory instrument which has been devised heretofore for this purpose is the one illustrated in the Petroff Patent No. 1,465,720. This instrument had the disadvantage, however, that it was difficult to form the spring clip thereof so as to have it squeeze tightly enough on the open end of the test tube to provide a firm, tight grip for the instrument and without subjecting the tube to the danger of being broken under the additional stresses incurred during usage. In order to overcome this disadvantage, it was found necessary to make the Petroff instrument so that the needle supporting leg of the clip was approximately as long as the outer leg of the clip. While this modification reduced the difficulty of obtaining a fairly secure hold on the tube and the possibility of breakage of the tubes, it accentuated other inherent disadvantages of this instrument. For example, it brought the gripping end of the holder nearer the blunt end of the needle which materially increased the tendency of the needle to flex and it rendered even less rigid the needle holding leg of the spring clip, thus giving the needle a tendency to reciprocate or to shift as a whole with respect to the glass tube during usage. This condition was highly undesirable and necessitated the user to exercise the greatest of care to prevent the causing of unnecessary pain to the patient. The Petroff instrument also had the disadvantage, due to the fact that the needle extends an appreciable distance into the test tube, that the needle must necessarily have a relatively large bore in order to compensate for the frictional resistance of the interior walls of the needle to the flow of the blood. As the cost of the needle and the pain caused to the patient is in direct proportion to the size of the needle, it will be apparent that the needle required in the Petroff construction will be more expensive and cause more pain to a patient than a smaller needle. A long needle such as used by Petroff is also objectionable because it has a greater tendency to

flex when inserted into the patient, thereby causing unnecessary pain to the latter and it is harder to clean and sterilize than a short needle. Furthermore, the method of connecting the clip to the needle in this construction is a relatively expensive one. These unsatisfactory conditions have caused the art to see if a more perfect and satisfactory instrument might not be found but, so far as I am aware, no one has yet succeeded in overcoming all of the disadvantages inherent in a device of this construction.

It is the purpose of the present invention to provide an improved blood collecting instrument which is free from all the aforementioned defects and which is of simple and inexpensive construction while at the same time strong, reliable and completely satisfactory for the purposes intended.

These objects are attained by so constructing the holder of the instrument as to form at its upper end a transverse extension or lip portion which is adapted to seat on the upper end of the test tube and to support the needle so that it extends only a short distance into the test tube, and to provide adjacent to such transverse lip a transverse channel-shaped portion which is so associated with the butt end of the needle that the clamping action of the instrument occurs at the upper end portion of the test tube.

The invention will be better understood from the following description, read in connection with the attached drawing which shows a preferred form of the invention and in which Fig. 1 is an enlarged front elevation of the instrument and the upper end portion of a test tube; Fig. 2 is a side elevational view illustrating the manner in which the instrument is mounted on a test tube ready for use, the upper portion of the test tube being partly broken away to show the manner in which the needle cooperates with the holder to secure the instrument to the test tube; Fig. 3 is a side elevational view, partly in section, illustrating the manner in which the instrument is attached to the upper end of the test tube; Fig. 4 is a top view of the parts shown in Fig. 1 and Fig. 5 is a sectional view taken along the line 5—5 of Fig. 2.

In the drawing, 10 designates the receptacle, such as the test tube illustrated, to which the instrument is attached while in use. The instrument itself is composed of a holder 11 provided on its upper end with an offset or transverse lip 12 which is in the nature of a flat plate and is disposed at an angle of slightly less than ninety degrees with relation to the body of the holder. This offset or lip 12 is adapted to seat on the

upper end of the tube 10 when the instrument is properly mounted thereon, as is shown more clearly in Fig. 2 of the drawing, and provides a fixed, non-springy support for the hollow or tubular needle 14 whose butt or terminal end is adapted to extend into the tube 10. The needle is secured to the offset support 12 by first providing the latter with an aperture 13 having a diameter only slightly larger than the exterior diameter of the needle so that the needle will fit therein with a snug fit. After the needle is inserted through the aperture and properly positioned with respect to the holder, the metallic material of the support 12 around the aperture 13 is compressed with the aid of a pair of opposed dies. As a result of this compressing operation the material of the support 12 is caused to flow into tight engagement with the exterior surface of the needle, compressing the latter to a slight degree to provide an annularly-shaped interlock as between the support 12 and needle 14. Thus the needle 14 is fixedly pivoted intermediate its ends on a relatively rigid support, thereby enabling the two ends of the needle to be flexed or bent independently of each other.

The body of the holder 11 except for a transverse channel-shaped section 15, is convexly formed from its line of juncture with the lip or plate 12 to its lower end, the degree of curvature of such body being substantially the same as the degree of curvature of the exterior surface portion of the test tube against which the body will rest so that the body will properly seat on such surface portion of the test tube. It will be noted also, from an observation of Fig. 2 of the drawing, that except for the channeled portion 15 and the lower end 16 of the body which is bent outwardly so as to provide a finger rest for the operator when manipulating the instrument, the entire body of the instrument is in engagement with the exterior surface of the tube 10 and this condition reduces materially any tendency of the body of the holder 11 to reciprocate on the glass tube once it has been properly mounted thereon. The channel-shaped or outwardly bowed portion 15 of the holder 11 is positioned intermediate a relatively short upper portion 17 of the body and a relatively long intermediate portion 18 of the body so that when the instrument is on the tube, the bowed portion 15 will bridge a portion of the upper end of the test tube with its curved lines of juncture with the body portions 17 and 18 in engagement with the exterior surface of the tube to provide two spaced lines of contact with the upper end portion of the tube.

As will be observed more clearly in Figs. 2 and 3 of the drawing, the needle 14 is inclined with relation to the plate 12 of the holder 11 and extends through the latter at a point spaced from the interior surface of portion 17 of the holder at the juncture of the same with the plate 12, a distance only slightly greater than the thickness of the wall of the glass tube 10. The blunt or butt end of the inclined needle 14 terminates at a point intermediate the curved lines of juncture of the bowed portion 15 with the body of the holder 11 and closer to its line of juncture with the body portion 18 than to its other line of juncture. The space between the terminal end of the needle 14 and the line of juncture of the bowed portion 15 with the body portion 18 is just enough to enable the upper end of the test tube 10 to be readily slipped therebetween into the space defined by the bowed portion 15 and the butt end of the needle, as is illustrated in Fig. 3 of the

drawing. The incline of the needle 14 is such that its terminal end is spaced from a longitudinal line connecting the interior surfaces of the lines of juncture of the bowed portion 15, less than the thickness of the wall of the tube on which the instrument is to be mounted, and is preferably closely adjacent to such line.

It will thus be seen, that in order to mount the instrument on the test tube 10, it will be first necessary to insert the open end of the tube between the terminal end of the needle 14 and the juncture of the bowed portion 15 with the body portion 18 and into the space defined by the bowed portion 15 in the manner illustrated in Fig. 3 of the drawing. The test tube is then turned toward the body portion 18 with its upper end pivoted against the interior surface of the bowed portion 15 and at the same time is forced up towards the plate 12 so that the upper end 20 of the tube slips between the body portion 17 and the butt end of the needle. The interior surface of the body of the holder at the junctures of the bowed portion 15 with the portions 17 and 18 thereof is smoothly curved so that the above operation is readily and easily accomplished in 25 one continuous movement. As the plate 12, due to the formation of the holder, is rigid relative to the needle, the butt end of the needle is displaced by the tube 10 and placed under a tension such that the upper end portion of the tube is 30 securely clamped between the terminal end of the needle and the spaced body portions 17 and 18.

It will be apparent from the foregoing description, that when the instrument is properly mounted on the test tube with the upper end of the latter in engagement with the plate 12, the instrument will be securely attached to the upper end portion of the tube and there will be substantially no tendency of the instrument to ride or shift relative to the tube during usage. Due to the fact that the bowed portion 15 of the holder is closely adjacent to the plate 12, the needle extends only a short distance into the tube thus 45 making it possible to use a relatively short needle, less than two inches in length. The shortness of the needle not only makes it easier to clean and sterilize but enables the use of a small gauge needle (19 gauge or finer) due to the lowered resistance to the flow of blood with the consequent advantages of being less painful to the patient and less expensive to manufacture. Even though the needle is finer, there is practically no danger of flexure in its use because of its 50 rigid support 12 and the tension which is applied thereto below the plate 12. By reason of the fact that the needle is spaced from a longitudinal line connecting the interior surfaces of the holder body portions 17 and 18 on each side of the bowed portion 15, a distance less than the thickness of the wall of the tube, the butt or terminal end of the needle and the holder portions 17 and 18 cooperate to firmly clamp the device to the tube. This distance of the terminal end of the needle 60 from the said longitudinal line and also the distance between the portion of the needle which extends through the plate 12 and the portion 17 of the holder are predetermined and depend upon the thickness of the wall of the receptacle on 65 which the device is designed to be used. Thus the device is constructed so that the distance of the terminal end of the needle from the said longitudinal line will be less than the minimum thickness encountered in a particular type of receptacle, while the distance between the needle and 70

upper end of plate 17 will be sufficiently greater than such minimum thickness to enable the plate 12 to be seated on the upper edges or rims of receptacles whose walls may vary from such minimum thickness. As the variances in the thicknesses of test tubes are not material, being in the nature of several millimeters from a minimum thickness, the portion of the needle below the plate 12 which is independently flexible with respect to such plate, will be displaced readily with respect to said longitudinal line to take care of such variances as the device is inserted on the tubes.

While I have illustrated and described a preferred embodiment of my invention, it will be apparent to those skilled in the art that various changes in the construction and arrangement of the parts may be made without departing from the spirit of the invention or the scope of the appended claims.

I claim:

1. A blood collecting device comprising a holder adapted to be mounted on the open end of a receptacle, a rigid supporting member provided on said holder, a needle extending through said member, the material of which said member is constituted being of greater density around the portion of the needle extending therethrough than in the remainder of said member and fixedly securing the needle to said rigid member to provide a fixed support for said needle intermediate its ends and to enable one end of the needle to be flexed relatively independently of the other, the butt end of said needle which is adapted to project into the receptacle on which the device is mounted, having a length less than the length of the holder and cooperable with said holder to clamp the device in position on a receptacle.

2. A blood collecting device comprising a holder adapted to be mounted on the open end of a receptacle, a needle supporting member provided on said holder and extending as a whole in a direction transverse to the central axis of the receptacle, said supporting member being rigid relative to the needle and adapted to seat on the receptacle, a needle mounted on said supporting member to enable its butt end to extend into the receptacle, said needle being fixedly secured to said member intermediate its ends to enable the oppositely extending end portions of said needle to be flexed relative to said rigid supporting member and the butt end of said needle and said holder being constructed and arranged to cooperate to clamp the device in position on the receptacle.

3. The combination of a hollow needle sharpened at one end and a holder adapted to support said needle on a receptacle, said holder including a needle supporting portion and a body portion having spaced surface portions adapted to engage the exterior surface of the receptacle on which the holder is to be mounted and connected by an intermediate portion spaced from a straight line connecting such surface portions, said needle being carried by said needle supporting portion to enable its butt end to extend into the receptacle and said needle extending in inclined relation to the body of said holder, the terminal end of the butt of said needle being positioned intermediate the spaced body surface portions and being spaced from said line a distance less than the thickness of the wall of the receptacle, whereby the butt end of said needle will engage under tension the interior surface of the receptacle in the region intermediate said spaced body surface portions.

ERROL R. LAWSHE.
